[57] CLAIM

The ornamental design for a candle anchor, as shown and described.

DESCRIPTION

FIG. 1 is a side elevational view of a candle anchor showing my new design, the opposite side being a mirror image;

FIG. 2 is a front elevational view thereof;

FIG. 3 is a rear elevational view thereof;

FIG. 4 is a top plan view thereof;

FIG. 5 is a bottom plan view thereof;

FIG. 6 is a front perspective view thereof on a reduced scale, the candle being shown in broken lines for illustrative purposes only.
